(57) CLAIM

The ornamental design for a combined ceiling fan blade and blade iron, as shown and described.

DESCRIPTION

FIG. 1 is a perspective view from below of a combined ceiling fan blade and blade iron in accordance with my design, illustrated in its environment;

FIG. 2 is an enlarged perspective view from below of the combined ceiling fan blade and blade iron in accordance with my design, illustrated in its environment;

FIG. 3 is an enlarged perspective view from below of the combined ceiling fan blade and blade iron in accordance with my design;

FIG. 4 is a bottom plan view of the combined ceiling fan blade and blade iron in accordance with my design;

FIG. 5 is a side elevation view of the combined ceiling fan blade and blade iron in accordance with my design; the opposite side being a mirror image of that shown

FIG. 6 is a proximal view of the combined ceiling fan blade and blade iron in accordance with my design; and,

FIG. 7 is a distal view of the combined ceiling fan blade and blade iron in accordance with my design.

The broken lines showing environmental structure are for illustrative purposes and form no part of the claimed design.

In FIGS. 3, 4 and 5, the Fan blade is shown broken away to indicate indeterminate length.
